(57) **CLAIM**

The ornamental design for a device for extracting and amplifying nucleic acid, as shown and described.

DESCRIPTION

FIG. 1 is a top front left side perspective view of a device for extracting and amplifying nucleic acid, showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the device for extracting and amplifying nucleic acid that form no part of the claimed design.

The drawings are shaded to indicate contrasting surfaces.
